United States Patent

Des. 237,643
Patented Nov. 11, 1975

237,643

PLANT RECEPTACLE

Hubert E. Christian, Phoenix, Ariz., assignor to
Dart Industries Inc., Los Angeles, Calif.

Filed Dec. 27, 1974, Ser. No. 537,011

Term of patent 14 years

Int. Cl. D11—02

U.S. Cl. D35—3 A

FIG. 1

FIG. 2

FIG. 3

FIG. 5

FIG. 4

FIG. 1 is a perspective view of a plant receptacle embodying my ornamental design;

FIG. 2 is a side elevation view;

FIG. 3 is a bottom plan view;

FIG. 4 is a top plan view; and

FIG. 5 is a cross-section view taken along the line 5—5 of FIG. 4.

I claim:

The ornamental design for a plant receptacle, substantially as shown and described.
